CLAIM

We claim the ornamental design for an insert for container, as shown and described.

DESCRIPTION

FIG. 1 is a top perspective view of an insert for container showing our new design;

FIG. 2 is a bottom perspective view thereof;

FIG. 3 is a side view thereof;

FIG. 4 is a top plan view thereof;

FIG. 5 is a bottom plan view thereof; and,

FIG. 6 is a perspective view thereof, shown in a position of use with an exemplary container.

The broken lines are shown for the purpose of illustrating both parts of the insert as well as environmental subject matter of an exemplary container. None of the broken lines form part of the claimed design.

1 Claim, 5 Drawing Sheets
